UNITED STATES PATENT OFFICE.

ELEAZER KEMPSHALL, OF CHEVY CHASE, MARYLAND, ASSIGNOR, BY MESNE ASSIGNMENTS, TO KEMPSHALL FAST COLOR TIP COMPANY, A CORPORATION OF NEW JERSEY.

SHOE-LACE.

1,073,496.

Specification of Letters Patent. Patented Sept. 16, 1913.

Application filed May 3, 1911. Serial No. 624,759.

To all whom it may concern:

Be it known that I, ELEAZER KEMPSHALL, a citizen of the United States of America, and at present a resident of Chevy Chase,

5 Maryland, have invented a certain new and useful Improvement in Shoe-Laces, and Particularly in the Tip or other Hardened Portion Thereof; and I declare the accompanying to be a full and accurate description thereof, reference being had to the accompanying drawing and to the claims for a specific statement of what I regard my invention to be.

10 The object of my present invention is to provide a lace with a celluloid tip, the celluloid impregnating the lace to form an anchor.

15 A further object of the invention is to provide means for temporarily binding the compressed end of a lace, and subsequently coating the binder with pyroxylin, the latter intermingling with the binder and impregnating the threads at the compressed end of the lace, whereby to form an effective anchor

20 between the tip and the lace.

25 In the accompanying drawing: Figure 1 is a side view of the finished article. Fig. 2 is a vertical sectional view of Fig. 1. Fig. 3 is a cross-section on Fig.

30 2, showing the lace pressed and dipped. Fig. 4 is a cross-section of a form in which the lace end is wrapped with a strip of adhesive material before dipping, and Fig. 5 is a cross-section of a form in which the lace

35 is primed with glue or other adhesive substance.

40 A indicates an ordinary lace having its ends rolled or compressed, as indicated at A' but one end of the lace being shown in the drawing. The compressed end A' is held in shape by a temporary binder 2, which may be in the form of permeable gummed cloth, or glue. After the binder is applied, the compressed end of the lace is provided with a coating of celluloid, which

45 extends through and intermingles with the binder material and impregnates the lace and forms, thereby, a homogeneous mass,

the celluloid taking hold of the lace and forming an effective anchor, whereby the 50 tip is absolutely prevented from pulling away from the lace.

In lieu of celluloid I may employ equivalent material, such as cellulose acetate, bakelite or similar substances, which will, like 55 the celluloid, take into and hold fast to the strands of the lace.

The temporary binder may be dispensed with, and the celluloid applied to the rolled or compressed end, in which case the celluloid impregnates the lace and intermingles with the strands in the same manner as previously described.

In some instances the laces are round, or are solid, and therefore the end need not 60 be further rolled or compressed, this being a matter which is in the discretion of the manufacturer.

What I claim and desire to secure by Letters Patent is:

1. A shoe lace having its end compressed, a strip of permeable adhesive substance surrounding the compressed end, and a coating of celluloid over the adhesive substance, the celluloid and the adhesive substance being 75 intermingled and impregnating the fibers of the compressed portion of the string whereby to form a homogeneous tip.

2. A shoe lace having its ends compressed, a temporary binder on each compressed end 80 of the lace, and a tip composed of material which permeates the temporary binder and impregnates the compressed ends of the lace.

3. A shoe lace having its end compressed, 85 and a tip comprising celluloid which impregnates the compressed end, the celluloid forming with the compressed end a homogeneous hard mass.

In witness whereof, I have hereunto set 90 my hand, this 3rd day of May, A. D. 1911.

ELEAZER KEMPSHALL.
